ROTARY PUMP

Elbert Fowler, East Cleveland, Ohio, assignor of
one-half to Helen Eaton Brennan, Cleveland,
Ohio

Application December 1, 1939, Serial No. 307,101

9 Claims. (Cl. 103—120)

This invention relates, as indicated, to rotary pumps and the like, it being apparent from the following description that the principles of this invention are in general applicable also to motors, meters and similar devices.

Rotary pumps have long been employed for a variety of uses among which the pumping of fuel in the feed line of internal combustion engines has become one of the most important. Such pumps are small and compact, requiring no valving means, have relatively few moving parts and may be operated at very high speeds. In the past, however, various operating difficulties have been encountered, among which may be mentioned the alternative properties of either pulsating delivery or mechanical shock to the vanes of the pump, excessive wear of the vanes due to centrifugal force which causes rubbing between the extremities of the vanes and the liner of the pump casing, and vapor lock which may arise due to heat generated by such excessive friction. Further difficulties similar to those enumerated above are occasioned by hydraulic shock due to differences of direction of motion of the rotating vanes and the direction of approach of the fluid to be pumped, by the fact that such pumps have in general exerted unequal hydraulic pressure on the bearings, and also by the entrapping and violent working of the liquid in certain parts of the pump with the resultant tendency to cause overheating and vapor lock when handling volatile liquids.

It is an object of the present invention to provide a rotary pump suitable for pumping fuels to internal combustion engines, for example, and which will be substantially free from the above enumerated disadvantages.

Another object of this invention is to provide a rotary pump which may be automatically adjustable as to discharge depending on the line pressure obtained.

Other objects of this invention will appear as the description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is an enlarged fragmentary view in cross section along the line 1—1 of Fig. 3;

Fig. 2 is a further fragmentary cross sectional view of the device indicated in part in Fig. 1, taken along the line 2—2 of Fig. 3;

Fig. 3 is a side elevational view of the device of this invention;

Fig. 4 is a view in cross section taken along the line 4—4 on Fig. 1;

Fig. 5 is a view taken along the line 5—5 on Fig. 1 in the same plane as line 4—4 but in the opposite direction;

Fig. 6 is a view taken along the line 6—6 on Fig. 1 with the casing removed, showing the inlet and outlet ports;

Fig. 7 shows one of said ports in section along the line 7—7 on Fig. 8;

Fig. 8 is a view in cross section along the line 8—8 on Fig. 3 and line 8—8 on Fig. 7; and

Fig. 9 is a view in cross section of one form of automatic discharge regulator designed to operate in conjunction with the pump of this invention.

Referring now more specifically to the above figures and especially Figs. 1 to 8, one preferred embodiment of the present invention will be described below. As best shown in Figs. 1, 2 and 3, the outer casing of the pump proper consists of two tightly fitting members 1 and 2 held in close engagement by bolts 3. Journalled in one end of casing member 1 is the drive shaft 4 to the inner end of which is keyed floating member 5 in turn keyed to shaft 6 which is journalled in bushing 7 in member 1 and bushing 8 in member 2. In this manner a lost motion connection on the order of a universal joint is provided so that unequal wearing of the bearings will not result from any slight misalignment with the driving means. A coil spring 9 serves to hold member 5 tightly seated on bushing 7 to reduce any leakage past such bushing of the liquid being pumped and likewise keeps shaft 4 tightly seated on thrust bushing 10. A channel 11 in casing member 1 leads to drainage orifice 12 adapted to be closed by a screw plug. By this means the casing may be drained of any liquid which may seep past said member 5.

Integral with shaft 6 is a substantially hemispherical shell 13 in which the rotor 14 of the pump is secured. The manner of assembling and inserting said rotor and associate parts is as follows. Said rotor comprises a cored hemisphere formed in two halves to permit assembly about the flaring skirt 15 of the non-rotating cam carrying member or stator 16. Said rotor is furthermore slotted to receive a plurality of blades or vanes 17 shaped to be held between said skirt 15 and the cam surface 18 when in position for operation.

The method of assembly is now apparent: said vanes are inserted in the two halves of said rotor, the rotor assembled about member 16, and the whole slipped over the end of shaft 6 and inserted in shell 13. Ring 19 is then screwed in place on shell 13, tightly clamping said rotor therein. Said rotor therefore revolves as an integral whole with shell 13 and shaft 6. Member 16 is held in non-rotating position by ball bearings 20 which engage grooves 21 in the upper portion of said member and engage similar grooves in the lower surfaces of internal bosses 22 on casing member 2 which may now be bolted in place. A certain degree of variable inclination of member 16 is therefore possible for reasons explained below.

As viewed in Fig. 1, the cam face is shown in section midway in the pumping zone and midway in the sealing zone between the intake and discharge ports. Intake port 23 and discharge port 24 (see Fig. 5) are located in the axially curved portions of said cam face 18. Between said ports are the so-called flat cam surfaces 25 and 26 of the pumping zone and sealing zone respectively, where the vanes neither recede nor advance from the rotor. It is obvious from the above description that the flow of liquid may be reversed simply by reversing the direction of rotation of said rotor.

As best illustrated in Figs. 6, 7 and 8, port 23 communicates with outer port 27 and port 24 with outer port 28 in the upper surface of member 16. On either side of said outer ports are flanges 29 parallel to grooves 21, said flanges making a sliding fit with coupling members 30 and 31 (see Fig. 3). A leak-proof seal may be obtained by means of packing 32 against which said coupling members are tightly held by screws 33 bearing on strips of bearing metal 34. The engaging surfaces of the holding ring 19 and member 16 are spherical in contour to allow universal movement of the member 16 relative to the ring 19. The ball bearings 20 and associated grooves prevent relative rotational movement between these parts while permitting a relative rocking movement in the plane of Fig. 1. This rocking movement is likewise permitted by the sliding fit with the coupling members 30 and 31.

It will be obvious from the above that the flow of liquid through the pump may be regulated by varying the inclination of member 16. As viewed in Fig. 1, the cam faces 18 are positioned for maximum discharge. By inclining said stator, member 16, the degree of extension of the blades 17 in the pumping zone may be decreased and the degree of extension in the sealing zone increased. When the extension of the blades from the rotor is equal in both zones the effective discharge will, of course, be zero. Further inclination will then cause the pump to discharge in the opposite direction since the former sealing zone will become the pumping zone, and vice versa. It is, therefore, apparent that the pump of the present invention may be reversed without reversing the direction of rotation of the rotor.

The means provided for thus varying the degree of inclination of the cam carrying member 16 and hence the discharge of the pump will now be described in detail. As best shown in Figs. 1, 2 and 6, the central opening in member 16 extends sufficiently in line with grooves 21 to permit the desired range of inclination. Of course, when the cam face 18 rests on the surface of the rotor member 14 no further inclination is possible in that direction. The discharge line 35 leading from port 30 has a branch line 36

which passes through casing head 31. Said branch line 36 communicates with an inner casing 38 containing a Sylphon 39. Adapted to be moved by expansion or compression of said Sylphon is a piston 40 acting on a lever 41 pivotally mounted on a boss in casing 2. An arm 42 integral with said lever engages a rock member 43 formed on member 16 by which said member 16 may be tilted in accordance with the degree of expansion or compression of said Sylphon. A guide member 44 extends from adjacent boss 22 beneath said rock member and an open collar 45 partially embraces shaft 6 to hold member 16 in position.

15 A spring 46 is housed in a hollow exterior boss 47 with one end bearing on the end of lever 41 opposite to that acted on by piston 40. The compression of this spring may be regulated by adjusting screw 48 and lock screw 49. Said housing is closed by screw cap 50. By means of this spring member 16 is held in position for maximum discharge except when there is sufficient pressure acting on said Sylphon to overcome said spring.

20 A further device is illustrated in Fig. 9 to be used to magnify variations in pressure in line 35 and pass such magnified effect on to the discharge regulating means above described. Said device comprises a fluid filled Sylphon 51 in a casing 52, said Sylphon being connected by piston 53 to diaphragm 54. Said diaphragm comprises a circular depressed member of synthetic rubber ("Duprene") secured about its edge between casing members 55 and 56 and sheathed between metal plates 57 and 58 except for a relatively small area about its circumference. As a result it may be calibrated within narrow limits. The device is attached to line 35 at inlet 59 and the liquid escapes at outlet 60; or outlet 60 may be closed and a side line connect line 35 to inlet 59. Inlets 61 and 62 on the other side of said diaphragm communicate with the outer atmosphere or with an air pressure source so that the desired back pressure may be maintained. Instead of branch line 36 shown in Fig. 3, Sylphon 51 is connected through coupling 63 to casing 38, the whole being filled with a substantially non-compressible liquid. It is now readily apparent that even a slight fluctuation in pressure in line 35 will be sufficient to cause a compensating adjustment in the discharge of the pump.

25 The flow of liquid being pumped from supply tank 64 will then be to inlet 31, cam face port 23, pumping zone 25 (as shown in Figs. 5 and 1) cam face port 24, outlet port 30, line 35, pressure magnifying device, and on to the engine or other destination.

30 To prevent mechanical shock to the vanes and yet obtain a non-pulsating delivery it is necessary that the cam face 18, except in the pumping and sealing zones, be a curve such that the sum of the retractive velocities of the vanes on the discharge side will be a constant; that is, the algebraic sum of the accelerations of retraction of the blades on the curve must equal zero. It will also be necessary that two or more vanes be traveling across said curve at the same time; i. e., that there be at least six equally spaced vanes in the rotor. Of course, it is also desirable for similar reasons that the cam curve on the suction side be such that the algebraic sum of the accelerations of advancement of the blades from the rotor equal zero. As the pump is reversible both cam curves will generally be so plotted in any case.

While spring means or the like may be employed to urge the vanes against the cam face, the vanes of the present invention are provided with tails 65 which give them a center of gravity so spaced from cam surface 18 that centrifugal force due to rotation of the vanes about the axis of the shaft 6 is sufficient to hold the vanes in close contact with the cam face. Of course, the inner and outer edges of said vanes comprise arcs concentric with the curve of ring 19.

Certain advantages of the above described construction are at once apparent. While centrifugal force is relied upon to hold the radially disposed substantially axially reciprocable vanes in close contact with the cam face nevertheless they are not impelled thereagainst with a force comparable to that in the case of pumps wherein the vanes oscillate toward and away from the center of rotation of the rotor. As a result, there is less wear of casing and vane ends, greater efficiency of operation, and less tendency to generate heat with resultant vapor lock in the case of the more volatile liquids.

Furthermore, in the case of the pump of the present invention the pressures on the bearings are much more constant than they have been with pumps of the prior art since the vanes do not move appreciably "off-center" from sealing zone to pumping zone.

As the vanes do not cross each other there is no violent working of entrapped liquid which is so likely to cause vapor lock.

When the device is employed as a motor there is, of course, no need to provide variable discharge means and the stator member may be fixedly positioned without provision for tipping. As above noted, although generally described and claimed as a pump, it is intended to include the device, as defined, within the scope of the claims whether it be employed as a motor, meter, or for other similar purposes. As a motor, it may often be advantageously employed in driving pumps also constructed in accordance with the present invention.

Various other combinations are obvious, such as that obtained, for example, by mounting the rotors of two pumps on the same drive shaft.

Other modes of applying the principle of the invention may be employed, change being made as regards the details described, provided the features stated in any of the following claims, or the equivalent of such, be employed.

I therefore particularly point out and distinctly claim as my invention:

1. In a rotary pump, a rotor, a stator, said stator and rotor having annular end surfaces axially spaced from and facing each other, a plurality of vanes carried by and axially movable with respect to said rotor, means maintaining said vanes in engagement with said stator surface, adjacent pairs of said vanes cooperating with said surfaces to define expansible pumping chambers therebetween, each of said vanes cooperating to define a pump chamber of different volume from one of the pump chambers defined by a next adjacent vane, said stator surface having diametrically opposed camming surfaces adapted to impart axial movement to said vanes upon movement of said vanes thereover, a fluid inlet port in one of said camming surfaces and a fluid discharge port in the other of said camming surfaces, and intermediate surfaces spacing said camming surfaces from each other, said intermediate surfaces being so formed to define the outer and inner limits of axial movement of said vanes.

2. In a rotary pump, a rotor, a stator, a plurality of sector-shaped vanes carried by and movable with respect to said rotor, said vanes occupying positions lying in planes containing the axis of said rotor and being pivotal about

their sector centers toward and away from said stator, said stator having an annular shaped surface facing said rotor and engageable with said vanes, means maintaining said vanes in engagement with said annular surface, adjacent pairs of vanes cooperating with said rotor and said annular surface to define expansible pumping chambers therebetween, each of said vanes cooperating to define a pump chamber of different volume from one of the pump chambers defined by a next adjacent vane, said annular surface having diametrically opposed camming surfaces adapted to impart pivotal movement to said vanes upon movement of said vanes thereover, and intermediate surfaces spacing said camming surfaces from each other, said intermediate surfaces being so formed to define the outer and inner limits of pivotal movement of said vanes with respect to said stator, a fluid inlet port in one of said camming surfaces and a fluid discharge port in the other of said camming surfaces, and means mounting said stator for adjustable rocking movement with respect to said rotor to vary the position of said camming surfaces and thereby the rate of pump discharge.

3. In a rotary pump, a rotor, a stator, a plurality of sector-shaped vanes carried by and movable with respect to said rotor, said vanes occupying positions lying in planes containing the axis of said rotor and being pivotal about their sector centers toward and away from said stator, said stator having an annular shaped surface facing said rotor and engageable with said vanes, and means maintaining said vanes in engagement with said annular surface, adjacent pairs of vanes cooperating with said rotor and said annular surface to define expansible pumping chambers therebetween, each of said vanes cooperating to define a pump chamber of different volume from one of the pump chambers defined by a next adjacent vane, said annular surface having diametrically opposed camming surfaces adapted to impart pivotal movement to said vanes upon movement of said vanes thereover, and intermediate surfaces spacing said camming surfaces from each other, said intermediate surfaces being so formed to define the outer and inner limits of pivotal movement of said vanes with respect to said stator, a fluid inlet port in one of said camming surfaces and a fluid discharge port in the other of said camming surfaces, said vanes being arranged on said rotor to provide at least two vanes in contact with said last named camming surface at all times, said last named camming surface being constructed in such manner that the algebraic sum of the accelerations of the vanes in contact with such surface will equal zero.

4. Apparatus as claimed in claim 2 together with fluid pressure means responsive to the pump discharge pressure for effecting a rocking movement of said stator.

5. Apparatus as claimed in claim 2 together with fluid pressure means for effecting a rocking movement of said stator, and means respon-

sive to the pump discharge pressure for actuating said fluid pressure means.

6. In a rotary pump, a rotor, a stator, a plurality of sector-shaped vanes carried by and movable with respect to said rotor, said vanes occupying positions lying in planes containing the axis of said rotor and being pivotal about their sector centers toward and away from said stator, said stator having an annular shaped surface facing said rotor and engageable with said vanes, means maintaining said vanes in engagement with said annular surface, comprising a tail portion on said vanes spaced from said stator and to one side of the vane pivot center, said tail portion being operative to position the center of gravity of said vanes to such side whereby centrifugal force due to rotation of said vanes about the axis of said rotor will be operative to move said vanes pivotally outwardly toward said stator, adjacent pairs of vanes cooperating with said rotor and said annular surface to define expansible pumping chambers therebetween, each of said vanes cooperating to define a pump chamber of different volume from one of the pump chambers defined by a next adjacent vane, said annular surface having diametrically opposed camming surfaces adapted to impart pivotal movement to said vanes upon movement of said vanes thereover, and intermediate surfaces spacing said camming surfaces from each other, said intermediate surfaces being so formed to define the outer and inner limits of pivotal movement of said vanes with respect to said stator, a fluid inlet port in one of said camming surfaces and a fluid discharge port in the other of said camming surfaces, and means mounting said stator for adjustable rocking movement with respect to said rotor to vary the position of said camming surfaces and thereby the rate of pump discharge.

7. In a rotary pump, a rotor, a stator, a plurality of sector-shaped vanes carried by and movable with respect to said rotor, said vanes occupying positions lying in planes containing the axis of said rotor and being pivotal about their sector centers toward and away from said stator, said stator having an annular shaped surface facing said rotor and engageable with said vanes, means maintaining said vanes in engagement with said annular surface, said means comprising a part secured to said stator and presenting an engaging surface facing said stator surface engageable with said vanes at a

point to one side of said stator and rotor surfaces, adjacent pairs of vanes cooperating with said rotor and said annular surface to define expansible pumping chambers therebetween, each of said vanes cooperating to define a pump chamber of different volume from one of the pump chambers defined by a next adjacent vane, said annular surface having diametrically opposed camming surfaces adapted to impart pivotal movement to said vanes upon movement of said vanes thereover, and intermediate surfaces spacing said camming surfaces from each other, said intermediate surfaces being so formed to define the outer and inner limits of pivotal movement of said vanes with respect to said stator, a fluid inlet port in one of said camming surfaces and a fluid discharge port in the other of said camming surfaces, and means mounting said stator for adjustable rocking movement with respect to said rotor to vary the position of said camming surfaces and thereby the rate of pump discharge.

8. In a rotary pump, a rotor, vanes having concentrically curved inner and outer edges radially disposed about the axis of said rotor and arcuately reciprocable axially of said rotor, a stator having an annular cam face positioned to contact ends of said vanes and cause their reciprocation upon rotation of said rotor, inlet and outlet ports in said cam face, and means for tilting said stator and cam face relative to the axis of rotation of said rotor to vary the reciprocation of said vanes.

9. In a rotary pump, a rotor, a stator, said stator and rotor having annular end surfaces axially spaced from and facing each other, a plurality of vanes carried by and axially movable with respect to said rotor, adjacent pairs of said vanes cooperating with said surfaces to define expansible pumping chambers therebetween, said stator surface having diametrically opposed camming surfaces adapted to impart axial movement to said vanes upon movement of said vanes thereover, fluid inlet and outlet ports respectively leading from the spaces between said rotor and said camming surfaces respectively, and intermediate surfaces spacing said camming surfaces from each other, and means for varying the inclination of said stator with respect to the axis of rotation of said rotor to vary the rate of discharge of said pump.

ELBERT FOWLER.
